ARM CHAIR

Lyman E. Woodard, Owosso, Mich., assignor to Lee L. Woodard Sons, Owosso, Mich., a co-partnership

Filed Oct. 12, 1959, Ser. No. 57,904

Term of patent 3½ years

(Cl. D15—1)

The characteristic features of my design reside in the configuration of the frame portion.

I claim:

The ornamental design for an arm chair, substantially as shown and described.
